CLAIM

The ornamental design for a gear shift for a truck, as shown and described.

DESCRIPTION

FIG. 1 is a front and left side perspective view of a gear shift for a truck showing my new design;

FIG. 2 is a rear and left side perspective view thereof;

FIG. 3 is a right side elevational view thereof;

FIG. 4 is a front elevational view thereof;

FIG. 5 is a front and left side perspective view of a gear shift for a truck showing a second embodiment of my new design;

FIG. 6 is a rear and left side perspective view of FIG. 5;

FIG. 7 is a right side elevational view of FIG. 5; and

FIG. 8 is a front elevational view of FIG. 5.

FIG.1

FIG.2

FIG.3

FIG.4

FIG. 5

FIG. 6

FIG. 7

FIG. 8
